UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

METHOD OF MAKING BAGS.

Application filed August 20, 1923. Serial No. 658,240.

My invention relates to a method of making bags, and the objects and particular features of the invention will appear as the description of the method proceeds.

5 Some of the features of the invention are disclosed in my prior applications for process of making bags, Serial Nos. 285,692, 285,693 and 285,694 filed March 27, 1919, and as to such features, this application is a 10 continuation of my said prior applications.

In the accompanying drawings, which diagrammatically illustrate my invention, Fig. 1 is a side view of the apparatus for forming a tube from a strip of fabric. Figs. 2, 3, 4 and 5 are sections on lines 2-2, 3-3, 4-4 and 5-5 respectively, of Fig. 1. Fig. 6 is similar to Fig. 5, showing an alternative form of tube. Fig. 7 illustrates the severance of the tube into two-bag lengths. Fig. 8 20 illustrates the formation of bags from the two-bag lengths. Fig. 9 illustrates a detail of the step shown in Fig. 8. Fig. 10 is similar to Fig. 8 showing an alternative form of reinforcement. Fig. 11 illustrates a cloth strip. Figs. 12, 13, 14 and 15 illustrate steps 25 in the formation of the strip shown in Fig. 11 into bags.

In the preferred form of my invention, a 30 paper strip, 20, is lead from a roll, 21, past a pasting device, 22, which pastes one edge, 23. The strip is then folded and the edges progressively brought together, as illustrated by Figs. 2, 3 and 4, and finally wound into a package, 24.

35 As will appear from Fig. 5, the tube, 25, will be thickest where the edges, 23, are lapped and pasted together. The result is that when layers of the tube are superposed, as is done in winding the tube, the pasted edges are pressed and held together. I prefer to leave the tube packed in this manner until the paste has somewhat dried. The same result, of pressing together the pasted 40 edges of the tube, may be obtained with other forms of tube, as illustrated in Fig. 6, for example.

I prefer to use a strip having designs 45 printed thereon, the designs for successive bag lengths being upside down relative to each other. I also prefer to have the strip bear indicating marks 27, 27^a, between adjacent designs bottom. It is desirable to use

the indicating marks, even where no designs are used.

I sever the tube, as illustrated in Fig. 7, 55 between the design tops, or along each indicating mark 27^a, thus forming a plurality of tube lengths, each of proper length to form two bags.

The tube lengths are arranged side by 60 side, and parallel seams 28, 29 are sewed across them. The indicating marks, 27, are very useful in arranging the lengths and sewing the seams at the proper places. I prefer to reinforce these seams by strips 30, 65 31, fed into the seam on opposite sides. Continuous strips are used, and may be fed from coils, as shown at 32, 33, Fig. 9.

The tube lengths are severed between the 70 seams, as at 34, and the reinforcing strips and threads are severed between the bags, as at 35, 36, thus completing two separate bags for each tube length.

Instead of parallel reinforcing strips, a 75 single broad strip, 37, may be used, as shown in Fig. 10, and two seams sewed through the strip, which is afterwards severed with the bag material therebetween as shown at 38.

A variation of the process, in which a 80 cloth strip is used, is illustrated in Figs. 11 to 15, inclusive. A strip 40, is shown wide enough to form two tubes. The sides, 41, 42, are folded in to the central line, 43, and parallel seams, 44, 45, are sewed along the 85 folded edges. The two tubes thus formed are severed, as shown in Fig. 12, and then reversed, as shown in Fig. 13. Such a tube may be formed into separate bags, as shown in Fig. 14, preferably by severing into two-bag 90 lengths, arranging the lengths side by side, sewing parallel seams, 46, 47, across the successive lengths, and severing between the seams, as at 48.

As shown, I use the designs 26', and indicating marks 27', corresponding to the designs 26 and marks 27 on the paper tube.

The sewing of parallel seams across two-bag lengths of tubing is very advantageous, as two-bag ends can be sewed as quickly as 100 could one, were the tube severed into one-bag lengths before the cross seams were sewed; and, moreover, sewing parallel seams and severing midway between them results

in uniform projection of the tube walls beyond the seams. This uniform projection of tube walls makes a sufficiently strong seam with the minimum use of fabric, and gives the bag end a neat appearance.

6. Storing the tube with the pasted edges held together until the paste is somewhat dried avoids opening the pasted seam during subsequent manipulation of the tube.

10. It is obvious that some of the advantages of this invention could be realized if the pairs of closures were formed across the tube before severance into two-bag lengths, or if lengths of any even number of bags 15 were formed and the necessary pairs of closures formed simultaneously or successively.

20. While various specific features cooperate to form a desirable method of making paper bags, the several features may be modified and used in other relations within the scope of the appended claims, without departing from the spirit of the invention.

What I claim is:

25. 1. The process of making bags from a tube, which consists in severing the tube into lengths, each of proper length to make two bags, sewing parallel transverse seams midway of each length, and severing each 30 length between the seams.

35. 2. The process of making bags from a tube, which consists in severing the tube into lengths, each of proper length to make two bags, forming adjacent closures across each 40 length, and severing the lengths between the closures to form two bags from each length.

45. 3. The process of making bags from a tube long enough to make two bags, which consists in making two adjacent closures 40 across the tube and severing the tube between the closures thereby forming two bags, each with a closed bottom and open mouth.

50. 4. The process of making bags, which consists in forming a tube long enough to make two bags and with an indicating mark properly positioned thereon, and, at the place indicated by the mark, forming two adjacent closures across the tube and severing the 55 tube between the closures to form a closed end for each of two bags.

55. 5. The process of making bags which consists in forming a tube with a series of indicating marks thereon at intervals of two bag lengths longitudinally of the tube, severing the tube midway between the marks, and, at places indicated by the marks, forming two parallel closures across each severed off length and severing the lengths between 60 the closures.

65. 6. The process of making bags which consists in forming a tube with a series of designs, with the designs on successive bag lengths relatively upside down and with indicating marks between each pair of ad-

jacent design bottoms, severing the tube between each pair of adjacent design tops, and thereafter, at places indicated by the marks, forming two closures across each length and severing the lengths between the closures. 70

7. The process of making bags which consists in forming a tube with a series of designs, with the designs on successive bag lengths relatively upside down, dividing the tube into lengths, each long enough to form two bags, by severing the tube between the adjacent tops of the designs, forming two closures across each length between the bottoms of the designs, and severing the lengths between the closures. 75

8. The process of making bags which consists in forming a tube with a series of designs thereon, with the designs on successive bag lengths relatively upside down, and forming two adjacent closures between each 85 pair of adjacent design bottoms, and thereby forming closures for the bottoms of all the bags.

9. The process of making bags which consists in forming a tube with a series of designs, with the designs on successive bag lengths relatively upside down, severing the tube between adjacent design tops, sewing parallel transverse seams between each pair of adjacent design bottoms, and severing the 95 tube between the seams.

10. The process of making bags from a tube, which consists in severing the tube into lengths, each long enough to make two bags, sewing parallel transverse seams midway of each length, and severing each 100 length between the seams.

11. The process of making bags from a tube, which consists in severing the tube into lengths, each long enough to make two bags, 105 sewing continuous parallel seams midway across each of a series of lengths in succession, severing each length between the seams progressively as the seams are formed, and severing the thread between the bags, and thereby completing two separate bags from each length.

12. The process of making bags from a tube, which consists in severing the tube into lengths, each long enough to make two bags, 115 sewing continuous parallel reinforced seams midway across each of a series of lengths in succession, severing each length between the seams, and severing the thread and reinforcing material between the bags.

13. The process of making bags from a tube, which consists in severing the tube into lengths, each long enough to make two bags, sewing a pair of continuous reinforcing strips across each side of a series of lengths 125 by two seams each of which passes through an opposed pair of strips and the tube walls therebetween, severing each length between the seams, and severing the strips adjacent each bag after they are sewed thereto. 130

14. The process of making bags, which consists in pasting together the edges of a paper strip to form a tube, forming the tube into a package with the pasted edges pressed together, leaving the tube in such package until the paste is dry, thereafter severing the tube into lengths each long enough to make two bags, sewing parallel reinforced seams midway across each length, and severing each length between the seams. ¹⁰ In testimony whereof I have hereunto signed my name to this specification.

ADELMER M. BATES.
